United States Patent Office

Des. 173,733
Patented Dec. 28, 1954

173,733

MOTOR VEHICLE BODY

Alfred Anthony Juliano, Natchitoches, La.

Application December 9, 1953, Serial No. 27,991

Term of patent 14 years

(Cl. D14—3)

FIG. 1.

FIG. 2.

FIG. 3.

FIG. 4.

FIG. 5

To all whom it may concern:

Be it known that I, Alfred Anthony Juliano, a citizen of the United States, residing in Natchitoches, Natchitoches Parish, Louisiana, have invented a new, original, and ornamental Design for a Motor Vehicle Body, of which the following is a specification, reference being made to the accompanying drawings, forming a part hereof.

Fig. 1 is a front view in perspective of a motor vehicle body, showing my new design;

Fig. 2 is a top plan view of the vehicle body;

Fig. 3 is a side elevational view of the vehicle body;

Fig. 4 is a front elevational view of the vehicle body; and

Fig. 5 is a rear elevational view of the vehicle body.

I claim:

The ornamental design for a motor vehicle body, as shown.
